LIGHTING FIXTURE

Leo G. Stahlhut, Kirkwood, and Carl X. Meyer, St. Louis County, Mo., assignors to Day-Brite Lighting, Inc., St. Louis, Mo., a corporation of Missouri

Filed Apr. 27, 1960, Ser. No. 60,348

Term of patent 14 years

(Cl. D48—23)

FIG. 1

FIG. 2

FIG. 4

Fig. 1 is a perspective view, as seen looking upwardly from one end, of the lighting fixture showing our new design, the opposite end being the same;

Fig. 2 is a sectional view thereof taken on line 2—2 of Fig. 1 with the fluorescent tubes shown in broken lines for illustrative purposes only;

Fig. 3 is a reduced top perspective view thereof; and Fig. 4 is a side elevational view of the lighting fixture. We claim:

The ornamental design for a lighting fixture, substantially as shown and described.
